RADIO CABINET

William J. Condon, Chicago, Ill., assignor to
Zenith Radio Corporation, a corporation of
Illinois

Application February 18, 1948, Serial No. 144,584

Term of patent 7 years

(Cl. D56—4)

To all whom it may concern:

Be it known that I, William J. Condon, a citizen of the United States, residing at Chicago, in the county of Cook and State of Illinois, have invented a new, original, and ornamental Design for a Radio Cabinet, of which the following is a specification, reference being made to the accompanying drawing, forming a part thereof.

Figure 1 is a top perspective view of a radio cabinet, showing my new design.

Figure 2 is an enlarged top perspective view of the portion of Figure 1 shown in solid lines, and

Figure 3 is an enlarged top perspective view of the portion of Figure 1 shown in solid lines, that portion being in a closed position.

The dominant features of this design reside in the portion shown by means of full lines in the drawing.

I claim:

The ornamental design for a radio cabinet, as shown and described.

WILLIAM J. CONDON.
